UNITED STATES PATENT OFFICE

PAUL C. DELAIZE, OF NEW YORK, N. Y., ASSIGNOR TO D'ORSAY PERFUMERIES CORPORATION, OF NEW YORK, N. Y., A CORPORATION OF NEW YORK

DESIGN FOR A COVER FOR A POWDER BOX

Application filed July 15, 1931. Serial No. 40,555. Term of patent 7 years.

To all whom it may concern:

Be it known that I, PAUL C. DELAIZE, a citizen of France, residing in New York, in the county and State of New York, have invented a new, original, and ornamental Design for a Cover for a Powder Box, of which the following is a specification, reference being had to the accompanying drawing, forming part thereof.

The drawing represents a perspective view of a cover for a powder box showing my new design. The dominant feature of the invention resides in a cover having a substantially round top formed to simulate a series of

logs in side-by-side abutment, the rim of the cover being likewise formed to simulate a series of shorter logs in side-by-side abutment, combined with a handle of cylindrical shape simulating a small log which occurs at substantially the center of the top and in which the grain extends transversely of the log and at right angles to the lines of juncture of the simulated logs of the top and its rim.

I claim:

The ornamental design for a cover for a powder box substantially as shown and described.

PAUL C. DELAIZE.
